UNITED STATES PATENT OFFICE.

FRANK H. RILE, OF BUFFALO, NEW YORK.

SUMP.

No. 853,598.

Specification of Letters Patent.

Patented May 14, 1907.

Application filed September 4, 1906. Serial No. 339,199.

To all whom it may concern:

Be it known that I, FRANK H. RILE, a citizen of the United States, residing at Buffalo, in the county of Erie and State of New York, 5 have invented a new and useful Improvement in Sumps, of which the following is a specification.

My invention relates to roof and floor sumps and to means for securing the same in 10 place.

The object of my invention is to provide an efficient and durable sump, which will effectively exclude foreign matter from the 15 ejection pipe; which may be readily cleaned; and which may be readily and well secured to the roof, or floor.

My invention is not only useful as a roof sump, but is equally useful as a floor sump, especially in breweries, slaughter houses, and 20 like places, where floor drainage is desirable.

Referring to the drawings herewith, in which like characters of reference indicate corresponding parts,--Figure 1 is a plan view of the device *in situ*—a quarter being in 25 horizontal section just above the second strainer. Fig. 2 is a view one-half in elevation and one-half in vertical central section. Fig. 3 is a detail section in the same plane as the section portion of Fig. 2.

The main body, 1, is preferably, in the 30 form of a cone frustum and expanded into a flange at the upper end. A removable cover 2, having perforations 3 in the top and side openings 4 is seated in an annular seat 5 in the body 1 by means of a peripheral flange 6. It is preferable that the top of the flange 6 35 should lie flush with the top of the body 1 in roof sumps, and in floor sumps the cover 2 would, of course, be flat and lie in the plane 40 of the floor.

The bottom end of the body 1 is closed in, and preferably screw threaded, to connect with a cast or wrought iron ejection pipe 12.

Within the body 1 is placed a catch basin 45 7, which is preferably integral with a stand pipe strainer 8, having perforations 9. Over the top of the catch basin 7 is placed a strainer 10, having perforations 11 arranged radially and of increasing size toward the periphery, so that the bulk of the water and 50 any foreign substance of any size will pass downwardly (if at all) between the walls of the catch basin 7 and the walls of the stand pipe strainer 8 and be retained in that space.

It will now be seen that the coarser foreign 55 substances will be kept out by the cap 2;

that smaller particles which may pass through the first strainer will be stopped by the strainer cup 10; and that the still finer sediment will be arrested and held in the 60 catch basin 7. It will also be seen that the sump is readily cleaned by removing the cap 2, the strainer 10, and the catch basin 7.

In order to properly secure the sump to the roof or floor I have invented the following 65 means: 13 is a sheet metal flashing, which, upon its edges, is secured to the roof or floor material in any desired manner. 14 is a stop which encircles the sump in the usual manner. In order to secure the plate 13 to the 70 sump so as to form a perfectly tight and strong joint, I provide in the upper surface of the flange of the body 1 an annular dovetail groove 15 into which the inner circular edge of the flashing plate 13 is placed by 75 being flanged downwardly and inwardly as clearly shown in Fig. 3. The dovetail groove is then filled with molten lead, or other material serving the like purpose, and is filled flush with the top surface of the sump 80 body. This forms a perfectly tight strong joint. This means for securing the sump to the flashing is an important feature of my invention.

It will, of course, be understood that the 85 particular form and shape and material shown may be varied without departing from the spirit of my invention; and I therefore do not wish to limit myself to the specific construction shown and described, but 90

What I do claim is:

1. In a sump the combination with the body of a movable catch-basin and stand pipe strainer connected one with the other to form a single removable part, said strainer 95 being suspended within said basin to form a settling space.

2. In a sump the combination with a body of a movable catch-basin and stand pipe strainer connected one with the other to 100 form a single removable part, said strainer being centrally elevated within said basin to form an annular settling space.

3. In a sump the combination with the body of a movable catch-basin and stand pipe strainer connected one with the other to 105 form a single removable part, said catch-basin fitting to the walls of the body and said strainer being centrally elevated with said basin to form an annular settling space.

4. In a sump, the combination with the 110 body, of a removable strainer cap, a remov-

able catch basin and stand pipe strainer, and a removable strainer over said catch basin and stand pipe having radial perforations increasing outwardly in cross section to throw the foreign matter outside of the stand pipe into the catch basin.

5. In a sump, in combination with the body in the form of a cone-frustum, a removable strainer cap, a removable catch-basin and stand-pipe strainer, said basin and strainer connected one with the other to form a single removable part, said catch-basin cone-frustum shaped and fitting to the inner walls of said body and its periphery forming a seat for a removable strainer, a removable strainer seated over said basin and centrally elevated within said basin to form an annular settling space.

10. In a sump, in combination with the body, a flange at the top of said body, a re-

movable strainer cap fitting over said body and an annular groove in the upper face of said flange to receive the flanged edge of sheet metal flashing, and to receive a filling to secure said flange to said flashing. 25

7. In a sump, in combination with the body, a flange at the top of said body, a removable strainer cap removably fitting over said body, a catch basin and stand pipe strainer removably placed within said body, 30 an annular groove in said flange at the top of said body, to receive the flanged edge of flashing and a filling material, such as lead, for securing said flange to said flashing.

In testimony whereof, I have hereunto set 35 my hand in the presence of two witnesses.

FRANK H. RILE.
